UNITED STATES PATENT OFFICE.

RAYMOND WARE, OF BOSTON, MASSACHUSETTS.

INTERNAL-COMBUSTION ENGINE.

1,107,468.

Specification of Letters Patent. Patented Aug. 18, 1914.

Application filed January 24, 1913. Serial No. 744,054.

To all whom it may concern:

Be it known that I, RAYMOND WARE, of Boston, in the county of Suffolk and State of Massachusetts, have invented a new and useful Internal-Combustion Engine, of which the following is a specification.

I have noticed that the valve operating mechanism of internal combustion engines has been complicated and inaccurate and has 10 had much friction of moving parts and has required much lubrication and to overcome these objections I made my present invention which is a simple and accurate mechanism for producing continuous rotary, and 15 longitudinally reciprocating, movement of the sleeve valve of an internal combustion engine and has substantial practical advantages over anything heretofore known.

In the drawings: Figure 1 is an elevation 20 partly in section illustrating my invention as embodied in an internal combustion engine; Fig. 2 is a section on an enlarged scale on line 2-2 of Fig. 1; Fig. 3 is a fragmentary elevation on an enlarged scale; Fig. 4 is development of the cam surface of the sleeve; and Fig. 5 is a section on line 5-5 of Fig. 1.

A and B represent two internal combustion engine cylinders preferably cast together, the inlet port for the cylinders being shown at *a* and the exhaust port at *b*, and showing hollow sleeve valves C and D inserted in cylinders A and B respectively.

E and F are the pistons which work in 35 side, and are guided by, the sleeves C and D respectively, and which are connected to the connecting rods E' F' and transmit the power to the crank-shaft J.

K is a hollow main journal or center support for the crankshaft, midway between the two cylinders. This journal is supported in and by the web L which is part of the crank casing, being held rigidly in place by journal cap *m* and bolts *n*-*n*.

45 Integral with the lower end of each sleeve C and D and surrounding them are gears O and P which mesh together, there being a gear Q driving O and O in turn driving P. Crank shaft J drives bevel gear J' which 50 meshes with bevel gear J² the latter being rigidly connected to gear Q. This gearing causes the two sleeves C and D to rotate continuously and uniformly and completely 55 about their respective axes, and any number of sleeves could be operated in that way by gear Q.

In Fig. 2 I show a transverse section taken between the cylinders A and B, cutting the crank case through web L. R is a cast or drop-forged hanger, supporting two ball bearing rollers S-S, one on each side of the hanger, the axis of each being in the same line and parallel to a line through the crank shaft centers. Hanger R is bolted to the under side of the base of the cylinder pair casting by two bolts T-T. The exterior annular circumferences of the rollers S-S bear on the top surfaces of gears O and P. Below the rollers S-S are two similar rollers U-U, whose common axis is 60 parallel to and directly below that of rollers S-S. Rollers U-U are supported on the arbor W rigidly held in the web L as shown in Figs. 1 and 2, and bear on the bottom surfaces of the gears O and P. The top and bottom surfaces of the gears O and P constitute cam surfaces which form in each case, an unbroken surface around the sleeve, a radial line in the surface of any one of these cam surfaces intersecting the axis of the sleeve of which it forms a part, and being at right angles to its respective sleeve axis.

An outline of the two cam surfaces on one of the gears and their relative position is 65 shown in Fig. 4-which is a development of either gear O or P, one being the same as the other. It will be noted that during one-half a revolution of a sleeve about its axis in the direction shown it will be given a 70 gradual downward movement by the guidance of the roller S on the top cam surface X, and that during the remaining one-half revolution it is forced back to its top or original position by guidance of the roller 75 U on the bottom cam surface Y. Each roller moves in one direction only and this is an important matter in preventing wear of the roller. The action of the two rollers above and below the gear, and bearing on 80 their respective cam surfaces, gives one complete up and down movement for every complete revolution of the sleeve about its axis, the exact nature of the up and down movement being pre-determined by the circumferential contour of these two cam surfaces. The two cam surfaces on each gear are so 85 shaped and related that each roller is at all times in contact with its respective cam surface. This is desirable because the longitudinal line at the point of contact between each roller and its cam surface is not at the 90

100 105 110

same angle with the line connecting the centers of the rollers for the cam surfaces throughout the rotation of the sleeves.

This mechanism is applicable to an internal combustion engine having any number of cylinders, although it is best applied to one having multiples of two cast together, the above mechanism serving for two adjacent sleeves in the integral cylinder casting, it being preferable that, whatever the number of cylinders, the gears at the lower ends of the sleeves mesh together successively from the first to the last cylinder. As the gears on adjacent sleeves move up and down on each other, it is preferable that they be of the spur type although they could be of the helical type, with teeth making a very acute angle with the sleeve or gear axis, if so desired. The rollers revolving upon their stationary supports may be either plain, ball, or roller bearing, although ball or roller bearings are to be preferred on account of their longer wearing qualities, and the small amount of lubrication required, and in some cases it might be desirable to have fixed members instead of rolling members to engage the cam surface and thereby guide the sleeve.

In Fig. 5 I show sleeve C at the time of explosion the single port being then in its most remote position from the inlet and exhaust and its rotary position being indicated at Z, this position being also shown in Fig. 1 at Z'.

Packing rings A' and B' are provided in the cylinder head to prevent leakage.

Among the advantages of my invention are that it provides a more compact, simple, efficient and durable, and less costly internal combustion engine, having no valve pockets or exposed valve members; of lighter weight, fewer parts, more direct and shorter gas passages, having but one valve member per cylinder, being more easily and accurately timed, and having but one port to perform the functions of admission and exhaust, to provide for this port protection from the direct heat of compression and explosion, better protection against leakage, more uniform distribution of the lubricant over all parts of the valve member, causing more uniform and less wear on the valve member, piston, piston rings, and cylinder, doing away with the cam eccentric, or longitudinal valve actuating shafts customary in all types of 4-cycle internal combustion engines, and further providing by nature of its valve shape, location, and simple valve actuating mechanism, less difficult and less costly cylinder and crank case castings.

The action of the sleeve valve so as to show the coöperation of its valve port with the exhaust and inlet cylinder ports, assuming the cylinder in a vertical position, is as follows: At the time of the explosion in the

cylinder, or at the beginning of the power stroke, the sleeve is at or near its topmost position, the valve port being directly opposite the exhaust and inlet cylinder ports and covered by the cylinder head which projects into the sleeve valve from the top. As the piston goes down on the power stroke the sleeve valve rotates and at the same time moves downward with gradually increasing speed and the valve port in the sleeve moves in a direction toward the cylinder exhaust port. At the proper time the sleeve valve port appears from behind the cylinder head and begins to uncover the cylinder exhaust port allowing the spent gases to escape. As the sleeve valve continues to rotate the downward motion gradually decreases and the sleeve port uncovers more and more of the cylinder exhaust port until it is in exact registry with the exhaust port, and the maximum port opening is realized. Further rotation of the sleeve valve brings the valve port out of registry with the cylinder exhaust port and the cylinder exhaust port is closed to the working cylinder. At this point the downward motion of the sleeve has stopped. As the sleeve valve continues to rotate, shortly after the cylinder exhaust port is closed the sleeve valve port begins to uncover the cylinder inlet port. At this point the sleeve starts to move upward as it rotates and increases gradually as the cylinder inlet port is rapidly uncovered by the sleeve valve port. When the sleeve port is in registry with the cylinder inlet port the upward motion is at a maximum and then gradually decreases as the sleeve port moves out of registry with the cylinder inlet port and begins to disappear behind the cylinder head. Further rotation closes the cylinder inlet port and finally the sleeve port is entirely covered by the cylinder head and it arrives at its original position ready to repeat the cycle.

What I claim is:

1. An internal combustion engine comprising a cylinder having an inlet and an exhaust; a sleeve valve within the cylinder and having a port; a gear connected to said sleeve and having a cam surface; a guide to engage said cam surface; a piston within, and guided by, the sleeve; and means to rotate said sleeve completely about its axis, said guide giving to said gear and sleeve longitudinal motion during the rotation, and the longitudinal and rotary movements jointly contributing to bring said port in and out of registry with said inlet and exhaust.

2. An internal combustion engine comprising a cylinder; a sleeve within the cylinder and having a gear near one end and having two continuous annular cam surfaces, one at each end of the gear; a driving gear to engage said sleeve gear; two guides,

one to engage one cam surface and the other to engage the other cam surface to give the sleeve reciprocating longitudinal movement during the rotation.

5 3. A device of the character described comprising a cylinder; a sleeve valve in said cylinder and having a gear portion and two annular cam surfaces; a piston in said sleeve; two roller guides, one located in engagement with one cam surface to give the valve longitudinal movement in one direction and the other located in engagement with the other cam surface to give longitudinal movement to the valve in the other 10 direction; and a gear to engage said gear portion to give the sleeve valve continuous uniform rotary motion completely about its axis, said gear remaining in engagement with said gear portion throughout the longitudinal reciprocation of the sleeve.

4. A device of the character described comprising a cylinder having an inlet and an exhaust; a sleeve valve having one port only to coöperate with said inlet and exhaust 25 and having two annular cam surfaces; two roller guides, one located in engagement with one cam surface to give the valve longitudinal movement in one direction and the other located in engagement with the other cam surface to give longitudinal movement to the valve in the other direction; and a gear to engage said gear portion to give the sleeve valve continuous, uniform rotary motion completely around its axis, said gear remaining in engagement with said gear portion throughout the longitudinal reciprocation of the sleeve.

5. A device of the character described comprising a plurality of cylinders; a plurality of sleeve valves in said cylinders and each valve having a gear portion, the gear portions of adjacent valves being in mesh; a gear to mesh with the gear portion of one of said valves and thereby cause rotation of all 40 of them; and means to give longitudinal reciprocating movement to said valves during their rotation.

6. An internal combustion engine comprising a casing, having two cylinders each having an exhaust and an inlet; a sleeve valve within each cylinder and having one port only which port is adapted for successive registry with said inlet and exhaust, said sleeves being in adjacency and each 50 having a projecting gear surrounding its lower part, each gear having the same axis as the sleeve and being integral with it, the top and bottom of each gear forming continuous cam surfaces and the gears being in mesh; a piston within each sleeve valve; means to give to one of said gears continuous uniform, rotary motion completely about its axis; rollers held in stationary supports and engaging said top and bottom surfaces to 60 give one complete longitudinal reciprocating

movement to said valves during one complete rotation thereof.

7. An internal combustion engine comprising a casing having two cylinders; a sleeve valve within each cylinder and having a cam surface; a hanger mounted on said casing and supporting two rollers, each roller engaging one of said cam surfaces to give said sleeves longitudinal movement in said cylinders; and means to rotate said sleeves during said longitudinal movement.

8. An internal combustion engine comprising a cylinder casing; a sleeve valve within said cylinder; a gear connected to said sleeve and having a cam surface; a hanger mounted on the base of said casing; a roller supported on said hanger and engaging said cam surface to give said sleeve longitudinal movement in said cylinder; and means to rotate said sleeve during said longitudinal movement.

9. An internal combustion engine comprising a cylinder; a sleeve valve within said cylinder and having a cam surface; a piston within said cylinder; a crank case; a crank; a rod connecting said piston and said crank; a web in the crank case carrying a yoke; an arbor in said yoke; a roller mounted on said arbor and engaging said cam surface to give said sleeve longitudinal movement in said cylinder; and means to rotate said sleeve during said longitudinal movement.

10. In an internal combustion engine a sleeve valve with gear teeth on its lower portion; two continuous cam surfaces one at each extremity of the said gear teeth; guides to engage said cam surfaces; and a driving gear to engage said gear teeth, giving to said valve member simultaneous rotation and reciprocation.

11. In an internal combustion engine a piston; a cylinder; a sleeve valve within the cylinder, concentric with and surrounding the piston, with gear teeth on its lower portion and two continuous cam surfaces, one at each extremity of said gear teeth; guides to engage said cam surfaces; and a driving gear to engage said gear teeth, giving to said valve member simultaneous rotation and reciprocation.

12. In an internal combustion engine, a sleeve valve member having a single port with gear teeth on its lower portion; two continuous annular cam surfaces, one at each extremity of said gear teeth; guides to engage said cam surfaces; and a driving gear to engage said gear teeth, giving to said valve member simultaneous rotation and reciprocation.

13. In an internal combustion engine, a cylinder with an inlet and an exhaust port; a sleeve valve member concentric with said cylinder and having gear teeth on its lower portion; two continuous annular cam sur-

faces, one at each extremity of said gear teeth; guides to engage said cam surfaces; and a driving gear to engage said gear teeth, giving to said valve member simultaneous rotation and reciprocation.

14. In an internal combustion engine a cylinder with an inlet port and exhaust port; a sleeve valve member within the cylinder and having gear teeth on its lower portion and having a single port and being mounted to rotate said port into successive registry with said inlet and exhaust; a piston mounted to reciprocate within said sleeve valve; two continuous annular cam surfaces, one at each extremity of said gear teeth; guides to engage said cam surfaces and thereby reciprocate said sleeve; a driving gear to engage said gear teeth giving to said valve member rotation during said reciprocation thereby bringing said sleeve port into successive registry with the said exhaust and inlet.

15. In an internal combustion engine of the 4-cycle type a cylinder with an inlet port and exhaust port; a sleeve valve member within, and concentric with, said cylinder and having a single port and being mounted to rotate said port into successive registry with said inlet and exhaust; a piston mounted to reciprocate within said sleeve valve; gear teeth on the lower portion of said sleeve valve; two continuous annular cam surfaces, one at each extremity of said gear teeth; guides to engage said cam surfaces and thereby reciprocate said sleeve; a driving gear to engage said gear teeth giving to said valve member rotation during said reciprocation, thereby bringing said sleeve port into successive registry with the said exhaust and inlet.

16. In an internal combustion engine a piston mounted to reciprocate; a cylinder with an inlet port and exhaust port; a sleeve valve member inside the cylinder concentric with and surrounding the piston and having a single port and being mounted to rotate said single port into successive registry with said inlet and exhaust; gear teeth on the lower portion of said sleeve valve; two continuous annular cam surfaces one at each extremity of said gear teeth; guides to engage said cam surfaces and thereby reciprocate said sleeve; a driving gear to engage said gear teeth giving to said valve member rotation during said reciprocation thereby bringing said sleeve port into registry with the said exhaust and inlet.

17. In an internal combustion engine, a cylinder having an inlet and an exhaust port; a sleeve valve having one port only to coöperate with said inlet and exhaust and having gear teeth on its lower portion; two continuous annular cam surfaces, one at each extremity of the said gear teeth; two roller guides, one located in engagement with one

cam surface to give the valve longitudinal movement in one direction and the other located in engagement with the other cam surface to give longitudinal movement to the valve in the other direction; and a gear to engage said gear portion to give the sleeve valve continuous, uniform rotary motion completely around its axis, said gear remaining in engagement with said gear portion throughout the longitudinal reciprocation of the sleeve.

18. In an internal combustion engine comprising a plurality of cylinders; a plurality of sleeve valves in said cylinders and each valve having a gear portion, the gear portions of adjacent valves being always in mesh; a driving gear to engage with the gear portion of one of the said valves and thereby cause rotation of all of them; two continuous cam surfaces, one at each extremity of the said gear portion of each sleeve valve; and guides to engage each of said cam surfaces, giving to each sleeve simultaneous rotation and reciprocation.

19. In an internal combustion engine comprising a plurality of cylinders, each having an inlet and exhaust; a plurality of sleeve valves, each having a single port, and being concentric with and in said cylinders, each valve having a gear portion, the gear portions of adjacent valves being always in mesh; a driving gear to engage with the gear portion of one of the said valves and thereby causing rotation of all of them; two continuous cam surfaces, one at each extremity of the said gear portion of each sleeve valve; guides to engage each of said cam surfaces, giving to each sleeve simultaneous rotation and reciprocation, thereby bringing into registry the single port in each of said valves with its respective inlet and exhaust.

20. An internal combustion engine comprising a cylinder and a crank case; a sleeve in said cylinder having a gear portion and two continuous annular cam surfaces at the extremities of said gear portion; a hanger bolted to the base of the cylinder supporting a roller guide engaging one of the said cam surfaces; an arbor held in a supporting yoke in said crank case carrying a second roller guide engaging the other of said cam surfaces; a driving gear to engage said gear teeth on the sleeve valve, thereby giving to said sleeve valve continuous simultaneous rotation and reciprocation.

21. An internal combustion engine comprising a cylinder having an inlet and an exhaust; a piston; a crank case; a sleeve valve having only one port and being in the cylinder and surrounding said piston, having a gear portion and two continuous annular cam surfaces at the extremities of said gear portion; a hanger bolted to the

base of the cylinder supporting a roller 5 guide engaging one of the said cam surfaces; an arbor held in a supporting yoke in said crank case carrying a second roller 10 guide engaging the other of said cam surfaces; a driving gear to engage said gear teeth on the sleeve valve, giving to said sleeve valve continuous simultaneous rotation and reciprocation, thereby, bringing 15 into registry the said single port in the sleeve with the inlet and exhaust port in the said cylinder.

22. An internal combustion engine comprising a cylinder casing inclosing two cylinders; a crank casing; a sleeve valve in each of said cylinders of said cylinder casing; a gear portion on one of said sleeves meshing with a similar gear portion on the other, with continuous cam surfaces at the 20 extremities of each of said gear portions; two roller guides supported on a hanger bolted to the base of said cylinder casing, each engaging its respective cam surface at one extremity of each of the said gear 25 portions; an arbor held in a supporting yoke in said crank casing carrying two additional roller guides, each engaging its respective cam surface at the other extremity of each of said gear portions; a driving 30 gear to engage one of said gear portions, thereby, giving to said sleeve valves continuous simultaneous rotation and reciprocation.

23. An internal combustion engine comprising a cylinder having an inlet and an exhaust, a cylinder head fitted with packing rings projecting into said cylinder; a sleeve valve, having only one port, being located in the cylinder, and its upper portion 40 surrounding the cylinder head; a gear portion on the lower end of said sleeve valve; two continuous cam surfaces, one at each extremity of said gear portion; roller guides to engage said cam surfaces; a driving gear to engage said gear portion giving to said sleeve valve simultaneous rotation and reciprocation, thereby, bringing said sleeve valve port into registry with said in-

let and exhaust, and sealing and protecting 50 said sleeve port from leakage and the heat of compression and explosion, by masking said port between said cylinder and said cylinder head.

24. An internal combustion engine comprising a cylinder; a sleeve within the cylinder; a gear surrounding, connected to, and adapted to rotate, said sleeve and having a cam surface; a driving gear to engage and rotate said first-mentioned gear; and means to engage said cam surface to give 60 the gear and sleeve longitudinal movement during the rotation of the sleeve.

25. An internal combustion engine comprising a cylinder; a sleeve within the cylinder; a gear surrounding, connected to, 65 and adapted to rotate, said sleeve and having a cam surface; a driving gear to engage and rotate said first-mentioned gear; and a guide beneath said sleeve to engage said cam surface to give the gear and sleeve 70 longitudinal movement during the rotation of the sleeve.

26. An internal combustion engine comprising a cylinder; a sleeve within the cylinder; a gear surrounding, connected to, 75 and adapted to rotate, said sleeve and having a cam surface on its lower face; a driving gear to engage and rotate said first-mentioned gear; and means to engage said cam surface to give the gear and sleeve 80 longitudinal movement during the rotation of the sleeve.

27. An internal combustion engine comprising a cylinder; a sleeve within the cylinder; a gear surrounding, connected to, 85 and adapted to rotate, said sleeve and having an integral cam surface; a driving gear to engage and rotate said first-mentioned gear; and means to engage said cam surface to give the gear and sleeve longitudinal 90 movement during the rotation of the sleeve.
